UNITED STATES PATENT OFFICE.

JOHN KERCHER, OF CHICAGO, ILLINOIS.

TOBACCO-SMOKING PIPE.

Application filed July 26, 1924. Serial No. 728,285.

To all whom it may concern:

Be it known that I, JOHN KERCHER, a citizen of the United States, and a resident of the city of Chicago, county of Cook, and 5 State of Illinois, have invented certain new and useful Improvements in Tobacco-Smoking Pipes, of which the following is a specification.

My invention relates to tobacco smoking 10 pipes, and has for its paramount object the provision of an improved construction of this character which will be highly efficient in use.

Among its further objects, my invention 15 has in view the provision of a durable, sanitary pipe of the character specified, constructed with an outer and an inner bowl, inner bowl being suspended within and from the top region of, the outer bowl. According to an important feature of the invention, the suspension means includes a medium that is a poor conductor of heat, and all of the space between the bowls below 20 the region of suspension comprising a smoke or air chamber. The construction is such that liquid and poisonous substances resulting from combustion of the tobacco, will gather in the bottom of the outer bowl, and the pipe stem has communication with this 25 smoke chamber at a height whereat such liquid and poisonous substances cannot be drawn therethrough by the smoker.

Other objects will appear hereinafter.

The invention consists in the combinations 30 and arrangements of parts hereinafter described and claimed.

The invention will be best understood by reference to the accompanying drawings forming a part of this specification, and in 40 which,

Fig. 1 is a top plan view of my improved tobacco smoking pipe.

Fig. 2 is a vertical section taken on the line 2—2 of Fig. 1, and

Fig. 3 shows a side and a sectional view, respectively, of the inner and outer bowls in position for assembling, the ring in the outer bowl being shown as it appears before being engaged by the screw threads on the 50 inner bowl.

With more particular reference to the accompanying drawing, my improved pipe includes two bowls, an inner bowl 4 and an outer bowl 5, the inner bowl being considerably smaller in size than the outer bowl 55 and being suspended within the outer bowl

so as to provide a continuous smoke or air chamber 6 between the bottom and side walls of the bowls, the two bowls having a connection between them only at their 60 top ends.

According to an important feature of my invention, the outer bowl is made at its top end with a thickened region, preferably in the form of an exterior annular bead 7. On 65 its inner face, concentric with the bead 7, the outer bowl is provided with an annular groove 8 of angular form in cross section, having a horizontal wall 9 defining its bottom and an upwardly and inwardly inclined wall 10 opposite the bottom wall, so that this groove may be said to decrease upwardly in cross section. The inner bowl 4 is made at its top end with an overhanging flange 11, having its top surface curved outwardly as shown. Immediately below this flange, the bowl 4 has an annular region 12 which is tapered upwardly and outwardly, and which is also provided with male screw-threads 13.

For insertion in the groove 8, I provide a ring 14 having its outer circumference 15 formed to correspond with said groove. In cross section this ring is of larger dimension than said groove in order that it may be 80 compressed into the groove and still have its inner circumference 16 stepped inwardly from the interior surface of the outer bowl. This ring is preferably produced from cork, in order to provide a support that is a poor 85 conductor of heat, that is susceptible to an appreciable degree of compression, and that is adapted to retain screw threads when cut therein. The inner circumference of the ring 14 is made plain as shown in Fig. 3, 90 but when the inner bowl is inserted in the outer bowl, the male screw-threads 13 cut co-operating threads 17, as shown in Fig. 2, in the inner circumference of the cork ring. 95

The inner bowl 4 is provided at its bottom end with a plurality of apertures 18 through which the smoke may be drawn into the smoke chamber 6 and thence through the pipe stem 18' which has threaded engagement at 19 with the outer bowl at a 100 point just below the ring 14. In the use of my pipe, liquid and poisonous substances resulting from combustion gather in the bottom of the outer bowl where they cannot be drawn into the pipe stem by the smoker. 105

The flanged top 11 of the inner bowl is provided with two pairs of registering slots 110

20 and 21, respectively. The purpose of these slots is to provide means for the reception of a convenient tool such as a knife blade for the turning of the inner bowl in applying or removing the same.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. In a tobacco pipe, the combination 20 with an outer bowl and an inner bowl, of a ring member removably set in the outer bowl and projecting from the inner surface thereof, a threaded region which is inclined

inwardly and downwardly carried by the inner bowl and adapted to co-operate with 25 said ring, and to have a wedging action thereon, and means receptive of a turning instrument formed in the top of the inner bowl, substantially as described.

2. In a tobacco pipe, an outer bowl having an annular interior undercut recess at the top thereof, a ring member removably seated in said recess and having its outer periphery corresponding in form to said recess whereby to be wedged therein, and having its opening as defined by its inner periphery of less diameter than the interior diameter of said outer bowl, and an inner bowl fitting within said ring member and provided with screw-threads tapering in 30 opposition to the undercut recess screw-threaded into said ring member, substantially as described.

In testimony whereof I have signed my name to this specification.

JOHN KERCHER.
